UNITED STATES PATENT OFFICE.

THOMAS S. MASON AND EDWIN L. YUNGK, OF HARTFORD, CONNECTICUT.

CONTAINER.

Application filed May 6, 1925. Serial No. 28,437.

Our present invention has reference to containers and closures therefor.

An object is the production of a sanitary container and a closure therefor which frictionally engages the container in such manner as to establish a hermetical joint therebetween, and also in which the cover can be readily removed from the container and employed as a drinking cup.

10 A further object is the production of a container and a closure therefor of a simple construction which may be cheaply manufactured and marketed and of such shape and contour that when the closure is arranged on the container, an air-tight joint will be established therebetween, and further of such construction that the weight of the contents of the container will influence the said container and closure into tighter frictional engagement.

15 A still further object is the production of a container and closure that permits of a great number of closures and containers being nested together, to provide a small bundle for storage or shipment and which also permits of a number of nested closures being arranged upon one container, whereby the several closures may be individually used for drinking cups for the fluid in the container.

20 A still further object is the production of a container and a cover therefor, of cheap but waterproof material designed, after use, to be destroyed, and wherein the container and, if desired, the closure is provided with a handle foldable thereagainst when not in use and constructed preferably of the same material as the container and closure.

25 To the attainment of the foregoing and other objects which will present themselves as the nature of the invention is better understood, reference is to be had to the drawings which accompany and which form part of this application.

30 In the drawings:—

Figure 1 is a perspective view of a container and closure in accordance with this invention.

35 Figure 2 is a similar view but illustrating a slight modification.

Figure 3 is an approximately central vertical longitudinal sectional view through the construction illustrated in Figure 1.

40 Figure 4 is a similar sectional view through the closure.

45 Figures 5 and 6 are perspective views of

a container or of the closure for a container provided with a handle, the handle being shown in closed position in Figure 6.

50 Figures 7 and 8 are similar views illustrating a further modified form of handle construction, the handle in Figure 8 being closed.

55 Figures 9 and 10 are perspective views of containers and closures thereon provided with a further modified form of handle, the handle member in Figure 10 being in closed position.

60 Figure 11 is a side elevation of the improvement showing the bail attached to the handles of the container.

65 Figures 12, 13, 14 and 15 are cross sectional views of modified forms of containers or closures for containers.

70 Before attempting a detailed description of our improvement, we desire to state that the same is not to be restricted to any one particular use. Our improved container is designed for either solids or liquids, and both the closure and container may be constructed of the same material or the closure may be constructed of one material and the container of another. It is an object to produce a container and closure which may be cheaply constructed so that the same can be destroyed after the contents thereof are used, and therefore we may, by preference, construct our improvement of heavy waxed cardboard.

75 Referring now to the drawings in detail, the container, indicated by the numeral 1, is in the nature of a cylindrical member, the same having its bottom rounded or concaved inwardly, as at 2. The edge of the bottom is beaded, as at 3, which provides the side of the container, adjacent the bottom thereof, with a continuous groove 4. In this groove there is received the rounded flanged edge 5 of an auxiliary or reinforcing bottom member 6. The disk-like member 6 is concavo-convex in cross section, so that its inwardly rounded face will snugly contact the bottom 2 of the container. It will be apparent that should the bottom 2 be depressed, by the weight of the contents therein, the same will press upon the auxiliary bottom 6 to cause the rounded flanged edge thereof to more effectively grip the bead in the groove, and consequently reinforce the bottom of the container under all conditions.

80 85 90 95 100 105 110 The cylindrical casing 1 is formed with

an inwardly flared neck 7 that merges into an inwardly directed lip 8 at the mouth of the container. At or slightly above the juncture of the body proper with the flared neck 7 thereof, the container is formed with an outwardly directed rib 8'. The walls provided by this rib are flanged in opposite directions, the lower wall merging into a groove 9, which, of course, is continuous, and the lower wall provided by this groove is flanged downwardly and outwardly, in the same direction as the upper wall of the rib. The closure is broadly indicated by the numeral 10. The closure is flared inwardly from its lower end or mouth to its top to coincide with the flared neck portion 7 of the container 1, with which the said closure is designed for frictional engagement. The closure 10 has its upper edge rounded inwardly to provide an open bead 11. The inner wall of the bead is rounded, as at 12, toward the side of the closure, the said wall 12 merging into the top 13 of the said closure. The top is rounded inwardly, as clearly disclosed by the drawings, and it will be apparent that pressure by the contents of the container against the inwardly rounded bottom wall 2 of the container and the inwardly rounded top wall 13 of the closure will have a tendency to bulge the top wall 13 outwardly, with the result that the rounded inner portion 12 of the open bead 11 will be forced into frictional engagement with the inner wall of the neck. The open bead receives therein the lip 8 in the mouth of the closure, and the said lip snugly engages with the inner wall of the said bead. The open or mouth end of the closure 10 is formed with a groove 14. The groove defines opposite angle walls adapted for frictional contact with the angle walls provided by the rib 8 of the container. The lower angle wall provided by the groove 14 merges into an outwardly directed angularly disposed skirt portion 15 which is in frictional contact with the lower angle wall provided by the groove 9 in the container. The skirt in Figures 2 and 4 of the drawings is dispensed with.

We have stated that the container proper may be constructed of different material from the closure therefor, but either the container or closure is constructed of slightly yieldable material so that when the closure is pressed over the mouth of the container the coengaging parts thereof, above described will be brought into frictional engagement, and it will be thus noted that the container is not only closed but is hermetically sealed by the arrangement of the closure thereon.

It may be further desirable to provide the container and the closure therefor with handles.

In Figures 5 and 6 the handle 16 is formed

from a single strip of suitable bendable material, preferably waxed cardboard. The strip is folded upon itself, and the confronting ends of the same are suitably attached. Of course, if desired, the strip may be in the nature of a U-shaped member. The strip has only its portion 16' attached to the container or the closure, and is formed with fold lines 16'', at diametrically opposite points on its inner and outer arms. By such construction the handle may be brought to the position illustrated in Figure 5 of the drawings, when the same is desired for use and may be folded flat, as illustrated in Figure 6 of the drawings when not required for use.

In Figures 7 and 8 a container or the closure therefor is provided with another form of handle. The handle 20 is centrally folded upon itself and, at its said folded portion, is attached to the container or the closure in any desired or preferred manner. The handle 20 is centrally provided with an opening 20', serving as a finger hold or for the reception of the eye ends of a bail when two of such handles are employed. The active position of the handle is disclosed by Figure 7 and the inactive position by Figure 8.

In Figures 9 and 10, the handle is also constructed of a single piece of material having its central portion 17 secured to both the container and the closure therefor. From its said central portion the handle is provided with spaced score lines 17' affording flaps 18 outward of the said fold lines. These flaps are provided with finger or bail openings and when the handle is in active position the flaps have their outer edges swung against each other, as disclosed in Figure 9 and when in inactive position the said flaps are brought against the outer face of the closure and container.

In Figure 11 we have illustrated the bail 19 attached to the opening or eye portions of the handle construction disclosed in either of Figures 7-8, 9-10.

We do not desire to restrict our improvement to any particular form or shape and therefore in Figure 12 the improvement 21 is triangular in cross section. In Figure 13 the improvement 21 is square or rectangular in cross section.

In Figure 15 the container 22 presents five angular sides, while in Figure 14 the container 23 is substantially elliptical in cross section.

It is believed that the foregoing description, when taken in connection with the drawings will fully set forth the construction and advantages of our improvement to those skilled in the art to which such inventions relate, but we desire it understood that we do not wish to be restricted to the precise details of construction herein set forth and hold ourselves entitled to such

changes therefrom as fairly fall within the scope of what we claim.

Having thus described the invention, we claim:—

- 5 1. A container and a closure therefor, the container having an inwardly flared neck terminating in an inwardly directed lip, a closure having an inwardly bulged top and of a length approximately equaling that of the neck of the container and shaped complementary to said neck for frictional engagement therewith, and having its top formed with an inwardly directed open bead to receive therein the lip of the container.
- 10 2. A container and a closure therefor, the container having an inwardly bulged bottom and an inwardly flared neck that terminates in an inwardly directed lip, a closure of a length approximately equaling that of a neck of the container and shaped complementary to said neck for frictional engagement therewith and formed at its top with an open bead to receive therein the lip of the container.
- 15 3. A container and a closure therefor, one of which being formed of yieldable material, the container having an inwardly bulged bottom and an outer reinforcing bead therefor and having an inwardly flared neck portion terminating in an inwardly directed lip, the closure having an inwardly bulged top, an open bead at the upper edge thereof and its side wall flared complementary to the neck of a closure for frictional engagement therewith, and the open bead of the closure designed to receive the lip of a container therein when the closure is positioned on the container.
- 20 4. A container and a closure therefor, the container having an inwardly flared neck whose end is formed with an inwardly directed lip, and said container, at the juncture of the body thereof with the neck being formed with an outwardly directed rib, the closure having an inwardly bulged top and an open bead between the top and the side of the closure to receive the lip of the container therein, said closure having its body flared complementary to the neck of the closure and being formed, adjacent to its open end, with a continuous groove that receives the outwardly directed rib of the container therein when the closure is arranged on the container.
- 25 5. A container and a closure therefor, the container having its bottom rounded inward, the outer edge formed with an inwardly directed groove, a false bottom having a lipped edge to be received in the groove, the neck of a container being flared inwardly and terminating in an inwardly directed lip, and the body of the container at its juncture with the neck being formed with an angle bead, the closure having an inwardly rounded top formed at its periphery with an open bead, and whose body is flared outwardly and formed with an angled groove adjacent to the mouth thereof to receive the angle bead of the container therein when the closure is frictionally arranged thereover and the bead of the closure receiving therein the lip of the container when the parts are assembled.
- 30 6. A container and a closure therefor, the container having an inwardly flared neck terminating in the lip, the closure having an inwardly bulged top and being of a length approximately equaling that of the neck and shaped complementary thereto for frictional engagement therewith, an open bead at the top of the closure to receive the lip of the container therein.

In testimony whereof we affix our signatures.

THOMAS S. MASON.
EDWIN L. YUNGK.
